UNITED STATES PATENT OFFICE.

GEORGE F. SISBOWER, OF EAST ORANGE, NEW JERSEY, AND LOUIS E. PITTONI, OF NEW YORK, N. Y., ASSIGNEES TO NEW YORK COUCH BED COMPANY, OF NEW YORK, N. Y., A CORPORATION OF NEW YORK.

COUCH-HAMMOCK.

1,346,689.

Specification of Letters Patent. Patented July 13, 1920.

Application filed November 3, 1914. Serial No. 870,069.

To all whom it may concern:

Be it known that we, GEORGE F. SISBOWER, a citizen of the United States, residing at East Orange, in the county of Essex and State of New Jersey, and LOUIS E. PITTONI, a subject of the King of Italy, residing at New York city, county of New York, State of New York, have invented certain new and useful Improvements in Couch-Hammocks, the following being a full, clear, and exact disclosure of the one form of our invention which we at present deem preferable.

For a detailed description of the present form of our invention, reference may be had to the following specification and to the accompanying drawing forming a part thereof, in which—

Figure 1 is a perspective view of our device and

Figs. 2 and 3 show details.

Our invention relates to a couch-hammock having double wings adjustable both up and down and it includes certain construction details of general advantage that are also useful in couch-hammocks of different kinds.

Referring to the drawing, A represents the central section of the hammock; B and C represent the two wing sections. The frame of the central section includes the ordinary side rods 1 and 2 connected by end bars of which one is shown at 3. On this frame is stretched the metallic fabric of any desirable kind. On this metal fabric is placed the stuffed mattress D. It is formed of a top cloth d and a bottom cloth d' with the stuffing material between them. The top cloth d is continued down the sides and under the side-bars of the frame as shown in section in Fig. 2, and the two edges are connected by lacing as shown in Fig. 1. The bottom cloth d' is attached to the top cloth at each edge at or near the point d'. By this means the stuffed mattress is easily applied to and securely held in place on the frame, and a neat, finished appearance is imparted to the vertical sides of the mattress. The wing frames consist of a side-bar 4 or 5 with short end-bars 6 and 7 pivoted respectively to the extremities of the end-bar 3 of the central section, the arrangement being the same at that end of the hammock which is not shown in Fig. 1. Each wing frame is provided with a metallic fabric and a separate stuffed mattress corresponding to that

of the central section, the wing mattresses being each loosely connected to the central fabric so that they may be on the same level therewith or adjusted up or down with respect thereto, as shown in Fig. 1. The hammock is supported by vertical end strips G, attached at their lower ends to the end-bars 3, as shown in Fig. 1, or as shown in Fig. 3, wherein the vertical leg of end-bar 3 is turned up instead of down as in Fig. 1 and the side bars connected to the inner instead of the outer surface of the horizontal leg. The end strips G are of canvas or other fabric and have canvas reinforcing strips g, g sewed thereon and extending over the spreader-bar S at the top of each strip and also under and around the spreader-bar S² that is secured to the end-bar 3 as shown in Fig. 3. By this means the supporting strength of the end-strip G is materially reinforced while the reinforcing strips may be used to support the windshield in case it is used. The spreader-bar S is suspended by chains H, H that unite with a single chain K. Each wing section has a chain attached to its outer corner as shown at E and F and on the end of each chain is a hook that takes into one of the links of the corresponding chain H. This affords a very simple, strong and reliable device for supporting and adjusting the angle of elevation of the wings. This hammock is particularly designed for out-of-door sleeping and the two wings may be adjusted to a horizontal position to form, with the central section, a double bed, or they may be turned up vertically to form sides of a crib, or they may both be dropped down, or, finally, one may be adjusted up and the other down, as shown in Fig. 1, to permit a person to recline transversely on the hammock in a comfortable position.

What we claim as new and desire to secure by Letters Patent is:

1. A couch hammock frame comprising a pair of end angle-bars connected adjacent their ends by a pair of side rods, a fabric stretched between the end bars, end walls for the frame each including a strip of flexible material substantially co-extensive with said end bars and having horizontal spreader-bars secured to the upper and lower edges thereof, reinforcing strips at the vertical edges of said walls and having their ends bent around the upper and lower edges

of said walls and embracing said spreader bars, the lower edge portion of each wall being shaped to correspond to said end angle bars, securing elements extending through 5 said side rods, end bars and lower spreader bars for connecting all of said parts together, and means connected to the upper spreader bars for suspending the frame.

2. A couch hammock comprising a frame 10 including a pair of end angle-bars having a horizontal flange and an upwardly extending flange, a pair of side rods connecting the end bars and having their ends resting on said horizontal flanges, a fabric stretched between the end bars, end walls for the frame 15 each having its lower edge portion bent to

correspond to said end bars for engaging the outer and under faces of the flanges thereof, securing elements extending through said side rods, horizontal flanges and end walls 20 for connecting all of said parts together, and means connected to the upper spreader bars for suspending the frame.

In witness whereof, we have hereunto set our hands, before two subscribing witnesses, 25 this 30th day of October, 1914.

GEORGE F. SISBOWER.
LOUIS E. PITTONI.
